UNITED STATES PATENT OFFICE.

GUY W. BLACKBURN, OF ELGIN, ILLINOIS.

HEAT PENCIL.

Application filed September 7, 1926. Serial No. 183,875.

My invention relates to improvements in heat pencils and has for one object to provide a new and improved type of pencil, one whereby an electrically heated instrument 5 may be used to make marks on paper, fabric or the like by charring or burning the fabric.

Experience shows that in order to provide a pencil which can be used conveniently, it is not satisfactory to heat a heavy core and rely 10 upon conduction in the body of the core for heating the stylus or point. Experience shows that if the core is hot enough so that the stylus works at all, the body of the pencil, if small enough to be handled becomes 15 uncomfortably hot. Also experience shows that the hot point will when it contacts the paper or fabric be too hot and as one writes will very rapidly be cooled so that a line is drawn which is irregular. One object of my 20 invention is therefore to provide a heated member which in this case takes the form of a rotatable ball, which member is free to move as the pencil is moved along the paper, bringing newly heated parts of the ball or 25 member constantly in contact with the paper and carrying the cooled parts back into the heat zone. I provide therefore a heat zone or chamber, preferably heated by electricity with a writing ball, the major surface of 30 which is contained within the heat zone, only a minor part of the surface being exposed for writing, the ball being so supported that as writing takes place, it rotates constantly renewing the heated work contacting surface.

My invention is illustrated more or less 35 diagrammatically in the accompanying drawing, wherein:

Figure 1 is a side elevation;

Figure 2 is an enlarged sectional view;

40 Figure 3 is a section along the line 3—3 of Fig. 2.

Like parts are indicated by like characters throughout.

A is the anvil or platen. A¹ is a paper or 45 work, which is to be marked. The work may take the form of paper, cloth, wood or any object which can be marked, colored or affected either by charring or otherwise by the heat of a stylus.

B is a handle of such size that it can be 50 held conveniently in the hand. The drawing in Figure 1 is preferably about actual size, but might be smaller or larger as the case may be. The handle is hollow. It may be 55 made of metal, bakelite, wood, or any suit-

able material as desired. At the lower end of the handle it terminates in a forked head made up of two parallel prongs B¹ B² inclined to the axis of the handle. B³ is a cap at the outer end of the handle through which 60 passes a double wire cord B⁴, leading to any suitable source of electric power. On the under side of the prong B¹ are contact plates B⁵ B⁶, one of the wires of the cord terminating at each contact plate.

C is an insulating socket. It may be of any suitable material, perhaps of asbestos, mica composition, bakelite or anything else. This socket is slidable in the prong B², being limited in its movement therein by means of the set screw C¹, having a small cylindrical tip C² engaging a slot C³ in the socket C. The upper end of the socket slides in the under side of the member B¹. The socket C is rounded at its lower end, is hollow and is 70 necked down at C⁴ to contain the stylus ball C⁵ which is preferably of nicrome or some similar material. C⁶ is a ball supporting plunger, cupped as at C⁷ to engage the ball C⁵. This plunger is preferably a jewel, such 75 as is used for watch bearings. Surrounding this jewel and extending down around a large part of the ball is a very fine resistance wire coil C⁸. This coil terminates at one end in a contact screw C⁹, extending up along the 80 inside of the socket C⁴, and at the other end passes out through the socket and extends up through a groove C¹⁰, terminating at the contact screw C¹¹. The screws C⁹ and C¹¹ are 85 in opposition to the contact plates B⁵ B⁶. 90

D is a filler of insulating cement closing the space between the member C⁶ and the socket C in which the wire of the coil C⁸ is connected. This cement holds all the parts together so that the ball is held snugly in engagement with the socketed end of the member C⁶ by the necked down part of the socket C, the coil being held in place around it and the jewel held in place in the socket to form what amounts to a unit structure. D¹ is a 100 coil spring interposed between the member B¹ and the member C⁶, these two members being pocketed to engage the ends of the spring to prevent its displacement. When the stylus is out of action, this spring will 105 throw the socket down to break the electric circuit. When the operator begins to write he presses on the surfaces, and compresses the spring and closes the circuit through the heating coil.

The volume of the ball and the jewel and the length of the coil is so small that it is not necessary to keep the parts heated at all times. It heats sufficiently to write almost 5 instantaneously. The outer portion of the ball will be heated some by conduction, but this heat will be taken up so rapidly by the surface over which the ball passes that it will soon be cooled, and as the stylus passes 10 over the surface, the ball rotates in the jewel bearing allowing the cooled surface to travel back into the heating zone constantly replacing it by a heated surface coming out of the heated zone. Since the ball is supported in 15 the jewel and held there by the outer socket so that it is free to rotate, this rotation of the ball as it travels along the work takes place no matter in what direction the stylus is moved, thus making it possible to make any 20 kind of a line, at the same time always insuring that by the rotation of the ball a newly heated part of the ball will be presented to the work thereby giving accurate lines of substantially constant character. 25 Of course, if it were desired to do away with the automatic element, it would be only necessary to dispense with the spring and connect the wires directly to the screws C^9 and C^{11} , when the operation of the device 30 would be exactly the same as before.

I claim:

1. In a stylus for marking objects by heat, a work contacting member, means for heating it, and a support wherein the member is 35 movably mounted to present constantly renewed heated surfaces to the work as it travels therealong.
2. In a stylus for marking objects by heat, a material contacting ball, means for heating that part of it which is out of contact 40 with the material, and a support in which the ball is free to rotate to present constantly renewed heated zones to the work as it travels therealong.
3. In a stylus for marking objects by heat, a work contacting member, means for heating it, and a support wherein the member is 45 movably mounted to present constantly renewed heated surfaces to the work as it travels therealong, a heating chamber within the 50

support enclosing that part of the member which is out of contact with the work.

4. In a stylus for marking objects by heat, a material contacting ball, means for heating that part of it which is out of contact with the material, and a support in which the ball is free to rotate to present constantly renewed heated zones to the work as it travels therealong, and a heating chamber within the support enclosing that part of the ball which is 55 out of contact with the work. 60

5. A stylus for marking objects comprising a ball, a socketed plug in which the ball is free to rotate, a casing enclosing ball and plug and holding them in working relation, a heating element in the casing surrounding a part of the ball and plug to heat them, the ball being free to rotate with respect to the 65 plug and casing. 70

6. A stylus for marking objects comprising a ball, a socketed plug in which the ball is free to rotate, a casing enclosing ball and plug and holding them in working relation, a heating element in the casing surrounding a part of the ball and plug to heat them, the ball being free to rotate with respect to the plug and casing, and a handle in 75 which the casing is mounted. 80

7. In a stylus for marking objects by heat, a heated work contacting member, a support in which the member is permanently mounted, an electric coil therein and surrounding the member, a handle for the support, and means for closing a circuit through the heating coil when the handle and support are 85 pressed against the work. 90

8. In a stylus for marking objects by heat, a forked handle, an electric conductor extending therethrough, contact members in the handle, a stylus socket slidable in the 90 handle, the contact members thereon adapted to engage the contact members on the handle, yielding means for separating them, adapted to be compressed to close a circuit when the tool is used. 95

Signed at Elgin, county of Kane, and State of Illinois, this 30th day of August, 1926.

GUY W. BLACKBURN.
